J. W. SOHN

METHOD AND APPARATUS FOR BEAMING WARP

Filed July 27, 1921

UNITED STATES PATENT OFFICE.

JOHN W. SOHN, OF ROXBOROUGH, PENNSYLVANIA, ASSIGNOR TO A. T. BAKER & COMPANY, INC., OF PHILADELPHIA, PENNSYLVANIA, A CORPORATION OF PENNSYLVANIA.

METHOD AND APPARATUS FOR BEAMING WARP.

Application filed July 27, 1921. Serial No. 487,882.

To all whom it may concern:

Be it known that I, JOHN W. SOHN, a citizen of the United States, residing at Roxborough, county of Philadelphia, and State of Pennsylvania, have invented a new and useful Improvement in Methods and Apparatus for Beaming Warp, of which the following is a full, clear, and exact description, reference being had to the accompanying drawings, which form a part of this specification.

This invention relates to an improved method and apparatus for winding warp beams, particularly binder warp beams for pile fabric.

As is well known to the art, binder warp beams for weaving some fabric of this character contain in the neighborhood of 4880 warp threads or ends.

20 The object of my invention is to provide a method of beaming such warp and a device for carrying out the method in which the human element is eliminated to a very great extent, so that I am enabled to provide a 25 beam without broken ends as well as a beam in which each thread has been wound under substantially the same tension in its proper position on the beam so that the length of all the ends is substantially the same.

30 In carrying out my invention for a beam having 4880 ends, I provide a number of beams, for example, four, each with 1220 ends, place these beams in parallelism on suitable supports in which they are free 35 to rotate. I then conduct the ends from two of the beams about tension members to a roll in front of a measuring device and interpose between some of the tension devices guiding reeds and an automatic stop 40 device. This stop device is arranged to stop the machine if any of the ends are broken or slack. The ends from the other two beams pass around and through similar devices to the roll in front of the measuring 45 device. The ends from the four beams then pass from said roll about a measuring drum and around a roll beyond the measuring device, the two rolls together with the measuring drum also forming a tension device. 50 The ends then pass from the last roll through a guiding reed which maintains the different ends in their prearranged positions to the beam on which they are wound.

The four beams from which the final beam

is wound may be beamed in any desired 55 manner, but I prefer to beam them from separated threads each drawn from a separate source, and in their passage from the source to the beam I pass them around suitable tension devices so as to place an equal 60 tension on each end as it passes to the beam. I also provide suitable stops for stopping the machine if any of the ends are slack or broken.

Fig. 1 of the drawings is a side elevation 65 in diagram of one form of apparatus for carrying out the first step of my process.

Fig. 2 is a similar view of an apparatus 70 for carrying out the final step of winding a beam having a large number of ends.

In Fig. 1 of the drawings the reference character 5 designates the creel for supporting the required number of tubes 6 of yarn to make up a beam of warp having, for example, 1220 ends or warp threads.

The threads from each spool or tube passes through a stop which is arranged to stop the entire machine if the thread on the tube is broken. The stops are connected electrically in the usual manner with a suitable annunciator to indicate to the operator the location of the broken end, so the broken end can readily be traced and spliced. Each thread passes from its guides and stop on the creel through a guide eye on a board 7.

The various ends pass from the guide eye board 7 under the over guide rollers 8 and 9, and then through a separating device 10, consisting of a plurality of wire eyes similar to heddles, in which alternate threads 90 pass through the eyes while the others pass between the wires forming the eyes. One-half of the ends then pass over a separating bar 11, while the other half passes under said bar. The ends then pass from the bar 95 11 through a reed 12 and a supplemental stop device 13, which are arranged to keep the various ends separated so that the stop 13, which controls electrical devices, will stop the beamer if any of the ends are slack 100 or broken, as hereinafter described.

14 is a guide roller over which the ends pass from the stop device 13, and 14' is a measuring drum about which the ends pass from the guide roller 14 to a guide roller 15. 105 16 is a second separating bar below the guide roller 15, one-half of the ends passing around one side thereof while the other half

passes about the other side. 17 is a second reed between the bar 16 and the warp beam 18 on which the ends are wound. B is a bearing, there being one on each side of the machine for supporting the warp beam 18. 19 is a tension device or press for the warp beam comprising a longitudinal bar, which engages the ends or warp threads as they are wound on the beam, and which bar is carried by two weighted levers which are arranged to hold the bar against the wound warp with an equal pressure throughout the winding of the beam, by means of suspended weights.

15 The machine is driven by suitable mechanism hereinafter described to cause the ends to be drawn from the various tubes 6, around and through the various guides and separating devices, as well as the electrically controlled stops, by the rotation of the warp beam 18. The various guides are arranged to place the ends under tension and also to maintain the various ends separate from each other as well as to guide the various ends to their proper positions on the warp beam.

If any of the ends should become slack or broken between the measuring drum and the stop 13, the machine will be immediately stopped, and after the operator has spliced the end and placed it under the proper tension between the measuring drum and a point back of the stop device, the machine can again be set into motion.

35 It frequently occurs that an end breaks between the guides on the creel and some of the guides between the creel and the measuring drum; and very frequently the end will be picked up by one of the other ends and drawn ahead, thereby before the stop on the creel has time to fall into stopping position, and as the broken end continues to be drawn from the tube, the stop on the creel will fail to act.

45 By placing a supplemental stop-device adjacent to the measuring drum or near the point of greatest tension of the ends, I am enabled to stop the machine if any of the ends break close to the beam, and thereby avoid broken ends of the beam, as well as stop the machine if an end should be broken and picked up by another end and carried forward before the creel stop acted.

55 In the construction shown, the beam is driven by means of a pulley 20 connected to the beam in any desired manner, which is in turn driven from a pulley 21 by a belt 22. 23 is a driving pulley on the shaft of the pulley 21 driven by a belt 24 from any suitable source. The pulley 23 is arranged to be connected to the pulley 21 by means of a clutch 25 which is arranged to be thrown by hand to connect the pulleys to each other and is retained in driving relation by an electrically actuated latch 26. This latch is

arranged to release the clutch to stop the machine when the latch magnet 27 is energized.

28 is a battery or source of electrical energy one pole of which is connected to a contact 29 on the stop 13. 30 are contacts one on each side of contact 29 which are interconnected and are connected to one pole of magnet 27. The other pole of the magnet is connected to the other pole of the battery. 70 The stop 13 is provided with a plurality of circuit closing fingers 31 of the usual type, there being one for each warp thread or end, and are arranged to separate the threads, while the tension on the ends will hold the 80 fingers out of engagement with contacts 29 and 30. If one of the threads should become slack or broken, its circuit closing finger will drop and close the circuit through the magnet 27, release the clutch 25 and stop the 85 machine. The stops on the creel each comprises a pivoted finger 32 having an eye through which the thread passes from the tube or bobbin 6 to its eye in the board 7. The finger 32 is connected to one pole of the 90 battery 28 and 33 is a contact connected to one pole of magnet 27, the arrangement being such that when any of the threads break near the tube, its finger will drop, close the 95 circuit through magnet 27, and stop the machine.

The second step of this process may be carried out by apparatus, such as shown in Fig. 2, in which four beams such as beams 18, wound on an apparatus such as shown 100 in Fig. 1, each having, for example, 1220 ends, are supported in parallel relation to each other as indicated at 18^a, 18^b, 18^c and 18^d in bearings 18^e, 18^f, 18^g and 18^h respectively. The ends 34^a and 34^b from beams 18^a and 18^b respectively pass over a guiding and tension roll 35, then through an expansion reed 36, stop 37, around guiding and tensioning rolls 38 and 39, a measuring drum 40, another guiding and tensioning roller 41, 110 and a second expansion reed 36^d to the beam 42 on which they are wound. The ends 34^c and 34^d from beams 18^c and 18^d pass over and through similar devices 35^a, 36^a, 37^a and 38^a to the roll 39, and from which roll they 115 pass around and through the same devices to the beam 42 as the ends from the beams 18^a and 18^b. As the ends from the different beams 18^a, 18^b, 18^c and 18^d in their travel 120 to the beam 42 pass about similar tensioning devices, the tension on the four sets of ends from the beam 41 will be substantially equal. As the length of the different ends on beams 18^a to 18^d are substantially the same, the tension of the ends 34^a to 34^d between the 125 beams 18^a to 18^d and the first tension devices will be substantially the same, and as the same tension is applied to the various ends from the different beams, the length as well as the tension of each of the 4880 ends on 130

beams 18^a to 18^d will be substantially the same. The second tensioning device 36^d will be substantially the same as the first, and as the tension of the ends 34^a to 34^d is substantially the same, the tension of the ends 34^a to 34^d between the beams 18^a to 18^d and the second tensioning device 36^d will be substantially the same, and as the same tension is applied to the various ends from the different beams, the length as well as the tension of each of the 4880 ends on 130

beam 42 wound by this method will be substantially the same. If desired, I may use a pressing and tensioning device such as 43 on the beam 42 during the winding thereof, which is similar to the devise 19 shown in Fig. 1.

The beam 42 is driven by a pulley 44 which is in turn driven from a pulley 45 by a belt 46. The pulley 45 is driven from a pulley 47 which is in turn driven from any suitable source of power and is arranged to be connected to, and disconnected from, the pulley 45 by a clutch 48. 49 is a lever for shifting the clutch 48 into driving connection and is arranged to be held in such shifted position by a latch 50. The latch 50 is arranged to be withdrawn by a magnet 51 as hereinafter described to release the clutch lever, which will in turn shift the clutch and disconnect the machine from its driving mechanism.

The stop 37 is provided with two sets of circuit fingers 52, there being one finger for each end. These fingers are all alike, but are split up in sets as the ends are too close to each other to permit placing, for example, 2440 fingers in alignment, so therefore I divide the fingers into a plurality of sets. These fingers are arranged to close the circuit between one or the other of two contact devices 53 and a contact 54. The contacts 53 are connected to each other and one pole of a battery 55 or other suitable source of electrical energy, while the contact 54 is connected to one pole of the winding of the magnet 51, the other pole of the winding being connected to the other pole of the battery 55.

The stop 37^a is provided with similar fingers 52^a and contacts 53^a and 54^a. Contacts 53^a are connected to each other and the contacts 53, while contact 54^a is connected to contact 54.

By means of the above described connections, the circuit will be closed through the coil of magnet 51 if any of the ends should become slack or broken and permit its finger to fall, which will stop the machine, and as soon as the end has been spliced and the slack removed, the circuit will be broken by the lifting of the fallen finger, so that the machine can be again set into motion by shifting the clutch.

The advantages of my invention result from the provision of a method and apparatus for winding beams having a relatively large number of ends or warp threads in which substantially the same tension is applied to each end, so that all of the ends on the beam will be of substantially the same length and under the same tension.

A further advantage results from the provision of an apparatus of this character which is arranged to be automatically stopped if any of the ends should become

slack or broken and also so arranged that its driving mechanism will not be retained in driving relation until the defective end which stopped the machine has been mended.

Having now fully described my invention, what I claim and desire to protect by Letters Patent is:

1. The method of beaming warp having more than a thousand ends of substantially the same length and under substantially the same tension, which comprises unwinding a plurality of separated threads and imparting to them a progressive and equal travel toward an end holding beam and maintaining the threads under substantially the same tension by first drawing them into a single group in a prearranged order, separating said group into a plurality of groups with the threads in a prearranged order, separating the individual threads from each other, then again drawing them into a single group in a prearranged order and winding the grouped threads on the end holding beam in such order, then unwinding the threads from a plurality of such wound end holding beams and imparting to each of the threads from all the beams a progressive and equal travel toward a warp beam so that the ends on the warp beam will be of substantially the same length and maintaining all the threads under substantially the same tension by drawing the threads from all of the end holding beams into a plurality of groups in a prearranged order, separating the individual threads of each group, then combining the several groups and maintaining the threads in a prearranged order, and finally winding the threads of all of the groups on the warp beam in such order.

2. The method of beaming warp having more than a thousand ends of substantially the same length and same tension, which comprises unwinding several groups of threads from an equal number of beams, the threads of each group being of the same length and tension and imparting to the threads of all the groups a progressive travel and equal travel toward a warp beam and maintaining all the threads under substantially the same tension by drawing the threads of a plurality of groups into a single group in a prearranged order, separating the individual threads of each group, then combining the groups into a single group and maintaining the threads in a prearranged order in the single group, and finally winding the threads on a warp beam in such order.

3. A beaming machine for beaming a warp having a large number of ends, comprising means for turnably supporting a plurality of sets of end supply beams in parallel relation to each other, means for turnably supporting a warp beam in parallel relation to the supply beams, means for ro-

4
tating the warp beam to wind the ends thereon, a guide roller for each set of supply beams over which the warp ends pass from the respective sets of supply beams in their passage toward the warp beam, a stop mechanism between each guide roller and the warp beam and each having electrical contacts for separating the individual threads passing thereto from its guide roller,
10 an electrically actuated stop motion for the means for rotating the warp beam, electrical connections including a source of electrical

energy between the stop motion and the electrical contacts and a guide roll between the stop mechanisms and the warp beam 15 over which all of the ends pass from all of the supply beams in their passage to the warp beam.

In testimony of which invention, I have hereunto set my hand, at Philadelphia, Pa. 20 on this 25th day of July, 1921.

JOHN W. SOHN.

Witness:

H. MAE WATSON.
